[57] CLAIM

The ornamental design for a front portion of a motor vehicle, as shown and described.

DESCRIPTION

FIG. 1 is a perspective view of a front portion of a motor vehicle showing our new design;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof;
FIG. 7 is a perspective view of a front portion of a vehicle showing a second embodiment of our new design;
FIG. 8 is a front elevational view of FIG. 7;
FIG. 9 is a rear elevational view of FIG. 7;
FIG. 10 is a right side elevational view of FIG. 7;
FIG. 11 is a left side elevational view of FIG. 7; and,
FIG. 12 is a top plan view of FIG. 7.

The portion of the motor vehicle shown in broken lines is for illustrative purpose only and forms no part of the claimed design.
